UNITED STATES PATENT OFFICE.

EDWARD G. HODGES, OF MILWAUKEE, WISCONSIN.

FUEL-SUPPLY DEVICE FOR CARBURETERS

1,367,143.

Specification of Letters Patent.

Patented Feb. 1, 1921.

Application filed October 28, 1919. Serial No. 334,053.

To all whom it may concern:

Be it known that I, EDWARD G. HODGES, a citizen of the United States, and a resident of Milwaukee, in the county of Milwaukee and State of Wisconsin, have invented a certain new and useful Fuel-Supply Device for Carbureters, of which the following is a specification:

The object of my invention is to provide a fuel supply device for carbureters, embodying a liquid elevating device and a float chamber of simple, durable and inexpensive construction.

More particularly it is my object to provide such a device preferably embodying a single casing with suitable partitions therein for providing a compartment for a float chamber with an ordinary float therein, another compartment above the float chamber, a third upper compartment, and to provide a valve between the last two described compartments operatively connected with a float, and to provide another valve operatively connected with said second float for controlling the air supply to the compartment in which the second float is located.

A further object is to provide in such a device a chamber, and mechanism therein for regulating the flow of fuel and maintaining the fuel in such chamber at a proper predetermined level, said means including an outlet valve, an air inlet passage, a valve therefor, a float operatively connected with both of said valves, and to provide a tube communicating with the air inlet passage between the valve therein and the chamber, said tube adapted to be extended to a vacuum creating means preferably by way of the intake manifold of the engine.

A further object is to provide such a device including a float chamber without an air vent.

A further object is to provide such a device including adjustable means, whereby the height of the float chamber with relation to the carburetor may be regulated as desired for varying the height of the fuel in the float chamber with relation to the discharge end of the fuel nozzle without varying the quantity of fuel in the float chamber.

With these and other objects in view my invention consists in the construction, arrangement and combination of the various parts of the device, whereby the objects contemplated are attained, as hereinafter more fully set forth, pointed out in my claims

and illustrated in the accompanying drawings in which:

Figure 1 shows a vertical, sectional view through a device embodying my invention. 60

Fig. 2 shows a plan view of the adjustable clamp device.

In the accompanying drawings, I have used the reference numeral 10 to indicate generally a carburetor body or casing having therein the fuel nozzle 11, which is supplied through a somewhat resilient feed pipe 12.

Suitably supported by means of the clamp device hereinafter more fully described, is 70 a casing 13 having therein a partition 14 below which is formed the float chamber 15, which communicates with the pipe 12. Spaced above the partition 14 is a second partition 16. Above the partition 16 is what 75 may be called the upper chamber 17, and between the two partitions is the intermediate compartment or chamber 18.

Extending laterally from the top of the float chamber 15 is a passage 19. Extending laterally from the bottom of the intermediate chamber or compartment 18 is a passage 20.

Between the passages 20 and 19 is a suitable partition 21 through which extends 85 an opening 22, at the upper portion of which is a valve seat 23.

Above the passage 20, outside the main casing, is a screw-plug 24 for permitting access to the valve 25 which is arranged to 90 coact with the seat 23. The valve 25 has a stem 26 extending downwardly.

Received within the float chamber 15 is a float 27 which is provided with an arm 28 pivoted at 29. The stem 26 extends laterally through a suitable slot in the outer end of the arm 28, and above and below the arm 28 are nuts 30 and 31 on the stem 26.

The partition 16 preferably is inclined upwardly slightly from its central portion 100 and is provided at its central part with a suitable opening 32 and a valve seat 33.

Extending upwardly from the valve seat 33 is a valve sleeve 34 which is provided at its lower portion with openings 35 for the 105 free passage of fuel.

Communicating with the upper part of the chamber 17 and extending upwardly therefrom is a tube 36 having at its upper end a head 37 and a valve seat 38.

Coacting with the valve seat 38 is a valve 39 which is mounted on a stem 40 which

projects downwardly into the chamber 17 and is operatively connected with a float 41. I preferably extend the stem 40 through the float 41 and connect it at its lower end with 5 the valve 42 which coacts with the valve seat 33. It is obvious that the stem 40 fits loosely in the tube 36 for permitting free passage of air from the valve 39 into the chamber 17 and to allow free passage of air 10 to the tube 44 from both the chamber 17 and around the valve 39.

The valve 39 is screwed on to the stem 40 so as to permit adjustment. A suitable perforated cover cap 43 is screwed on to the 15 head 37.

Communicating with the sleeve 36 is the pipe 44 designed to be connected with a suitable vacuum creating means, preferably the intake manifold of the engine.

20 A suitable vent means for the intermediate chamber 18 is provided by means of a tube 45 which extends from the upper portion of the chamber 18, and is opened to the atmosphere at a point above the fuel level 25 in the chamber 17.

Communicating with the upper portion of the chamber 17 is the fuel supply line or pipe 46.

30 The casing 13 is suitably mounted on the carburetor for adjustment with relation to the discharge end of the fuel nozzle, without varying the height of the fuel in the float chamber itself.

35 Mounted in the upper wall of the float chamber 15 is a removable screw-plug 48, and mounted in the top of the chamber 17 is a similar plug 49.

40 In the practical use of my device the parts are assembled and installed in proper relation with the fuel nozzle in the carburetor, connected with the fuel tank, and the intake manifold, and adjusted.

45 The plugs 48 and 49 are taken out and fuel is poured into the chamber 17. This fuel will first fill this chamber to such a height as to raise the float 41, for thereby opening the valve 42, thereupon the fuel will flow down through the intermediate chamber into the float chamber until the 50 float in the float chamber is raised to the point where it closes the valve 25, whereupon the plugs 48 and 49 are placed in position and the device is ready for use.

55 In the use of my device, the fuel is drawn from the fuel nozzle by the suction of the engine. As the fuel is drawn from the float chamber, it will be seen that the float therein is lowered for opening the valve 25 and permitting additional fuel to flow downwardly 60 from the chamber 18.

Fuel passes from the upper chamber 17 to the intermediate chamber and as result the float 41 is lowered, whereupon the valves 39 and 42 are seated.

A partial vacuum will be created in the 65 upper part of the upper chamber which will cause fuel to flow through the fuel line 46 into the upper chamber, until the fuel in such chamber is sufficient to raise the float 41, for thereby raising the valve 42 and 70 permitting fuel to flow into the chamber 18, and also raising the valve 39 and connecting the upper part of the chamber 17 with the atmosphere.

The vacuum in the chamber 17 is thereby 75 reduced and fuel will flow downwardly into the intermediate chamber.

With a device of this kind it will be seen that the float 41 is directly effected by the height of the fuel in the upper chamber at 80 all times, and it correspondingly directly acts on or effects both of the valves 42 and 39 at all times, so that with my structure the fuel in both the upper and intermediate chambers will be maintained at a practically 85 constant level.

With the devices now commonly in use the general structure is such that there is first a substantial period of time when fuel is drawn into a chamber, and then a substantial period of time when no fuel is drawn into such chamber.

With my device the mechanism is very sensitive to variations in the fuel height, so that a very small variation in such height 95 operates the valves 42 and 39. A very slight operation of such valves regulates the action of the vacuum creating means, so that the float 41 will be constantly moving up and down slightly for operating the valves 100 and thus maintaining the fuel level substantially constant in the chamber 17.

In this connection attention is called to the advantage of a structure of this kind where the vacuum pipe 44 may be connected 105 with the intake manifold and no special valve control other than that here shown is necessary.

Instantly when the valve 39 is opened the upper part of the chamber 17 is connected 110 with the atmosphere and similarly the vacuum pipe is connected with the air, so that air will be drawn therethrough to the intake manifold.

It is of course obvious that as soon as the 115 valve 39 is closed the engine will draw the air from the upper chamber.

On account of the construction just mentioned it will be noted that the pipe 44 will draw air either from the chamber 17 or 120 through the cap 43 at practically all times, so that the effect of connecting the chamber 17 with the intake manifold will be uniform all the while, and there will be no periods when such effect will be to increase the 125 richness of the mixture supplied to the engine, followed by other periods where the effect will be to decrease the richness of

such mixture as is the case with certain devices now in use, and I thereby avoid interfering with the regular carbureting processes of the engine.

5 It will be noted that I have provided a float chamber without the ordinary air vent.

When fuel is drawn from the fuel nozzle by a vacuum created in the carburetor, fuel

will flow from the float chamber 15. There

10 will then be created a slight partial vacuum in the upper portion of such float chamber.

The float 27 will be lowered for opening the valve 25, and fuel will then flow more freely

15 from the intermediate chamber 18 into the

float chamber, on account of the slight partial vacuum in the float chamber, than would be the case if the upper portion of the float chamber were open to the atmosphere.

It will be seen, therefore, that I maintain 20 an almost constant level of fuel in the float chamber.

The desirability for maintaining such a constant level in the float chamber is well-known to all students of the internal combustion engine.

25 It will of course be obvious that the upper and intermediate chambers and the mechanism in the upper chamber are intended for drawing fuel from a tank located below the level of the carburetor.

It will be seen that by loosening the clamp 47 the casing 13 may be raised or lowered, and thereby the float chamber may be raised or lowered for varying the height of the fuel 35 therein with relation to the fuel nozzle, without varying the quantity of fuel in the float chamber. The tube 12 is sufficiently flexible to permit of such adjustment.

It will be seen that I have provided a 40 simple mechanism for accomplishing the objects set forth early herein.

I realize that changes may be made in the construction and arrangement of the parts 45 of my device for the accomplishment of such objects, without departing from the real spirit and purpose of my invention, and it is my intention to cover by my claims any such changes in the structure which may be reasonably included within their scope.

50 I claim as my invention:

1. In a device of the class described, the combination of a carburetor body, a fuel nozzle therein, a float chamber, a tube leading from said float chamber to said fuel nozzle, a fuel chamber adjacent to said float chamber, a passage leading from said fuel chamber to said float chamber, a valve in said passage, a float in the float chamber operatively connected with said valve, said float chamber being closed except for the passage into the fuel chamber and the tube leading to said nozzle, whereby when fuel is drawn from the fuel nozzle and the fuel in the float chamber is lowered, a slight partial vacuum 55 will be created in the upper part of the float

chamber for assisting in drawing fuel from the fuel chamber into the float chamber.

2. In a device of the class described, a carburetor body, a fuel nozzle therein, a float chamber, a tube leading from the bottom of said float chamber to said fuel nozzle, a fuel chamber, a passage leading from the fuel chamber to the float chamber for conducting fuel from the fuel chamber to the float chamber by gravity, a valve in said passage, a float in said float chamber operatively connected with said valve, said float chamber being closed except for said passage and said tube, so that when fuel is drawn from the nozzle by suction, due to 70 partial vacuum, and such suction is suddenly stopped, a partial vacuum will have been created in the float chamber and overflow of the fuel nozzle will be prevented.

3. In a device of the class described; a fuel elevating and supplying means, comprising a fuel nozzle; a float chamber; a tube for connecting said float chamber with said fuel nozzle; an intermediate chamber; and an upper chamber; a valve controlled 90 passage leading from said intermediate chamber to said float chamber; having a valve seat; a valve for coacting with said seat; a float in said float chamber; means for operatively connecting said float with 95 said valve; a passage leading from said upper chamber to said intermediate chamber having a valve seat; a tube leading from the top of said upper chamber having a valve seat; valves for coacting with said 100 last two described valve seats; a float in said upper chamber operatively connected with said last described valve, for imparting positive movement thereto; a tube connected with said second described tube and designed 105 to be connected with a vacuum creating means; a carburetor chamber into which said fuel nozzle is projected; and means for supporting said float chamber at various heights with relation to said fuel nozzle.

4. In a device of the class described; a carburetor chamber; a fuel nozzle therein; a float chamber; means for conducting fuel from the float chamber to said nozzle; and a device for supporting said float chamber 115 on said carburetor chamber at different heights with relation to said fuel nozzle.

5. In a device of the class described, a carburetor body having a fuel nozzle therein, a float chamber, flexible means for conducting fuel from the float chamber to said nozzle, an adjustable device for supporting said float chamber at different heights, so that the level of the float chamber fuel may be varied with relation to the discharge end 120 of the fuel nozzle, without changing the height of the fuel level within the float chamber.

Des Moines, Iowa, September 15, 1919.
EDWARD G. HODGES.
